UNITED STATES PATENT OFFICE

LOUIS KOOPERSTEIN, OF ASTORIA, NEW YORK, ASSIGNOR TO WEST DISINFECTING COMPANY, OF LONG ISLAND CITY, NEW YORK, A CORPORATION OF NEW YORK

LIQUID-SOAP-DISPENSING DEVICE

Application filed February 8, 1929. Serial No. 338,481.

The object of the present invention is to provide a dispensing apparatus for liquid soap of a type comprising a plunger-operated discharge device which receives the liquid soap from a bowl mounted thereon, the soap flowing into the operating device by gravity.

The specific object of the invention is to employ a glass bowl for the liquid soap in conjunction with means for securing the bowl to the discharge device in such a manner that replacement of the bowl may be readily effected and a new bowl may be applied merely by fitting the bowl into position and turning a screw which may be reached by a screw driver through the open top of the bowl. The arrangement enables a very shallow seat for the bowl on the plunger operated discharge device, and the elimination of screw threads on the bowl at the base thereof.

The invention will be described with reference to the accompanying drawing in which

Fig. 1 is a side elevation of an embodiment of the invention, the bowl and its retaining devices being shown in vertical sections;

Fig. 2 is a fragmentary elevation of the lower portion of the bowl and its retaining disk;

Fig. 3 is a fragmentary view of the plunger discharge device and its seat for the bowl, showing the latter in section;

Fig. 4 is a sectional plan view of line 4—4, Fig. 1, and

Fig. 5 is a sectional plan view of line 5—5, Fig. 1.

In the drawings 1 indicates the plunger operated discharge device. It consists of a horizontal member having a flanged extension 1^x by means of which the device may be secured to a support by the screws 2. The device is formed with an internal bore 3 for containing the valve mechanism, said mechanism forming no part of the present invention and not being shown. The mechanism is actuated by a plunger 4 and the soap is discharged through a nozzle 5.

The top of member 1 is formed with an annular seat 6 having the upwardly projecting flange 7. The seat 6 is formed with

passageways 8 permitting the soap to flow down into bore 3. The seat is also formed with a threaded aperture 9 for the purposes later to be explained.

The bowl is shown at 10. It consists of a glass body having an annular flanged and threaded upper neck 11, adapted to receive a closure cap 12. Intermediate the cap and top edge of the bowl may be placed a washer 13. At its base the bowl is formed with an annular shallow depending neck 12^x at the top of which is a horizontal annular shoulder 14.

Cemented upon neck 12^x of the bowl is a retaining cup 15, preferably of metal, the upper wall of which engages annular shoulder 14. Retaining cup 15 is formed with openings 14^x adapted to lie in register with openings 8.

In order to insure that the bowl will be accurately placed in position so that the openings 14^x will lie in register with opening 8, retaining cup 15 is formed with two or more depressed seats 16, 16^x (Fig. 3) one of which will be of greater size than the other, and annular seat 6 is formed with inwardly projecting lugs 17 each corresponding in size to its respective depression 16.

The retaining cup is formed with a centrally located threaded aperture to receive a screw 18 so that the screw may pass through the cup and thence into threaded aperture 9 of the annular seat. On screw 18 is threaded a stop nut 18^x so that when the screw is rotated to withdraw its threaded end from annular seat 6, the screw will be retained in position on the retaining cup 15.

Retaining cup 15 may be made of metal finished to insure smooth contact with the walls of annular seat 6.

Having described my invention what I claim and desire to secure by Letters Patent is as follows:

1. In liquid soap dispensing apparatus a valve casing formed with an annular flanged seat provided with soap apertures and with a threaded aperture, in combination with a bowl having an upper neck opening adapted to be closed by a filler cap and a lower relatively shallow neck, an annular retaining cup cemented upon the last named neck and hav-

ing a soap aperture adapted to lie in register with the aperture of said seat and provided with a screw aperture, and a holding screw for securing the retaining cup to said seat,
5 the screw being in vertical alignment with the filler neck opening.

2. A device constructed in accordance with claim 1 in which the retaining cup and seat are provided with inter-engaging lug and
10 socket devices adapted to maintain the soap apertures in register.

In testimony whereof, I have signed my name to this specification.

LOUIS KOOPERSTEIN.
